UNITED STATES PATENT OFFICE.

JOSEPH F. GEARY, OF CHICAGO, ILLINOIS, ASSIGNOR OF ONE-HALF TO OLIVE H. CRANDALL, OF CHICAGO, ILLINOIS, AND ONE-HALF TO ANNIE E. SHARPLEY, OF MELROSE PARK, ILLINOIS.

GAGE DEVICE.

1,158,403.

Specification of Letters Patent. Patented Oct. 26, 1915.

Application filed July 28, 1915. Serial No. 42,329.

To all whom it may concern:

Be it known that I, JOSEPH F. GEARY, a citizen of the United States, residing at Chicago, in the county of Cook and State 5 of Illinois, have invented a new and useful Improvement in Gage Devices, of which the following is a specification.

My invention relates to improvements in gage devices for use in connection with the 10 platens of printing presses to furnish an adjustable stop against which the work, such as envelops or sheets of paper, to be printed, may be properly positioned relative to the type.

15 In the type of presses to which my invention more particularly applies, the space between the inner edge of the platen and the path traveled by the inking rollers is comparatively narrow and any gage device employed must be of such construction that it will not project into the path of the inking rollers. It is desirable, however, that the portion of the gage device against which the work is fed and for which it forms a 20 stop, have relatively great adjustment for different sized work and for positioning the work at different places on the platen, and it is to provide a form of gage device which projects into the space between the inking 25 rollers and the platen and affords the desired relatively great adjustment of the stop devices for the work, that I have devised my invention.

A further object is to provide a simple 30 and inexpensive form of gage which may be readily applied to position on the platen and by which exceedingly fine adjustments of the stop members for the work carried thereby may be effected.

40 Referring to the accompanying drawing, Figure 1 is a plan view of a platen of a press showing a pair of my improved gage devices positioned thereon with a sheet of paper held in position by the gage devices; 45 Fig. 2 is an enlarged broken section, taken at the line 2 on Fig. 1 and viewed in the direction of the arrow; Fig. 3 is a section taken at the line 3 on Fig. 2 and viewed in the direction of the arrow; Fig. 4 is a perspective view of the outer end of the threaded inner rod of the device and the discon- 50 nectible foot, coöperating therewith and acting as a stop for the paper; and Fig. 5 another form of foot which may be used

and which is desirable especially where the work to be printed is envelops.

An ordinary form of platen of a printing press is represented at 6, the platen having pivoted thereto, as indicated at 7 and 8 at its opposite ends, bails 9 and 10 respectively 60 which serve to clamp to the platen, the cushioning pad 11, usually paper.

My improved gage device in its preferred embodiment comprises a bearing member 12 containing an internally threaded opening 65 13, this bearing member by preference being provided with a relatively thin section 14 adapted to be inserted between the bail 10 and the covering 11, as represented, to hold it in firm position, the bearing member 12 70 resting upon the upper side of the bail 10. The device also comprises a sleeve member or tube 15, externally threaded as represented at 16 to correspond with the threads 13 with which it engages adapting it to move 75 endwise through the bearing member 12 when the member 15 is rotated as by turning it at the knurled section 17. The forward end of the member 15 is internally threaded as represented at 18, this thread 80 being preferably of the same pitch as the thread 16 but extending in the opposite direction. In other words, one of the threads 15 and 18 is a right-hand thread and the other thereof is a left-hand thread. A rod 85 19 having screw threads 20 of the same pitch and extending in the same direction as the threads 18 telescopes with the member 15 and engages at its threads 20 with the threads 18, the rod 19 being provided at its 90 outer end with the foot 21 against which the work to be printed is positioned and for which it forms a stop.

In the particular illustrated embodiment of my invention the forward end of the rod 95 19 is of reduced diameter as indicated at 22, its extremity being square as indicated at 23, and the foot member 21 is formed with a rearwardly projecting tube section 24 adapted to fit over the outer end of the rod 19 and engage at a squared section 25 thereof with the shouldered end 23 of the rod when the foot is positioned on the rod as shown in Fig. 2. The foot 21 of Fig. 4 is preferably formed of two sections, the tubular section 100 24 and a plate section 26 forming the foot proper which is provided along its lower edge with projections 27 at which the foot

bears against the cushioning material 11 on the platen, and with an outwardly turned flange 28 along its upper edge which serves to prevent the work applied to the platen, 5 from becoming displaced.

It will be readily understood from the foregoing that by rotating the member 15 in the bearing member 12, it will move in or out of the latter depending upon the direction in which it is rotated, and by reason of the fact that the threaded rod 19 is held, by means of the foot 21, against turning, this rod will be caused to move lengthwise in the same direction that the member 15 moves, but at twice the speed, inasmuch as the inner and outer threads on the member 15 are of the same pitch. It will be understood, however, that if desired these threads may be of different pitch.

20 The feature just described is of great benefit and advantage in a device of this character inasmuch as a relatively great range of adjustment may be provided to the foot member 21 with the minimum longitudinal movement of the member 15, which in moving lengthwise moves through the space between the rear edge of the platen and the path of the inking rollers which space of necessity is of limited width. Furthermore, 25 it will be manifest that a very minute and delicate adjustment of the gage device may be effected.

The foot member 21 is preferably constructed as described in order that, if desired, the rod 19 may be released therefrom to permit it to turn with the member 15 when the latter is rotated and thus effect adjustment of the gage device through the medium of the single thread 15 instead of the double thread as hereinbefore stated, it being desirable under some conditions of use that the adjustment which may be effected by the single thread 15, be utilized. To so adjust the device the operator would slip the foot member 21 away from the rod 19 to disengage its squared section 23 from the square portion 25 of the foot, whereupon the rod 19 would be free to rotate in the foot 21.

50 In the drawing my improved gage device is shown in the position in which it is placed when forming a stop for the lower edge of sheets of paper applied to the press, in which case it is preferred that at least two of the gage devices be employed as shown, the paper being fed against the faces of the feet 21, as shown in Figs. 1 and 2.

The construction illustrated in Fig. 5 is the same as that shown in Fig. 4 excepting that the flange 28 carries a tongue 29 which 55 is a desirable adjunct to the foot 21, especially where the objects to be printed and fed against the gage devices, are envelops. The foot, however, may be of any other suitable form.

65 If desired, instead of providing threaded

connections between the various relatively movable members, provision for adjustment may be otherwise made, as, for example, the threads may be omitted and clamping means, set screws or the like employed to maintain the adjustment. Thus, for example, the adjustable members which are connected with the bearing member may be adjustable relative to each other and to the bearing member by a sliding longitudinal movement, employing clamping means, set screws, or the like, for maintaining the adjustment.

70 While I have illustrated and described certain embodiments of my invention, I do not wish to be understood as intending to limit it thereto, as the same may be variously modified and altered without departing from the spirit of my invention.

75 I claim as new and desire to secure by Letters Patent:

80 1. A gage device for the purpose set forth, comprising a bearing-member, a member having threaded connection with said bearing-member, and a third, oppositely threaded, member having threaded connection with 85 said second-named member and provided with a stop surface for work fed to the press, said third member being adapted to be held against rotation when applied to position on a platen.

85 2. A gage device for the purpose set forth, comprising a bearing-member, a member having threaded connection with said bearing-member, and a third, oppositely threaded, member having threaded connection with 90 said second-named member and provided with a stop surface for work fed to the press, said third member being adapted to prevent rotation of said 95 third member when said device is applied to position on a platen.

100 3. A gage device for the purpose set forth, comprising telescoping members having threaded connection with each other, and a bearing-member, one of said telescoping members having threaded connection with 105 said bearing-member by threads oppositely inclined to those connecting said telescoping members together, and the other of said telescoping members being provided with a 110 surface against which the work is fed when 115 the device is applied to a platen.

120 4. A gage device for the purpose set forth, comprising telescoping members having threaded connection with each other, a bearing-member, one of said telescoping members having threaded connection with said 125 bearing-member by threads inclined opposite to those connecting said telescoping members together, and a foot carried by the other of said telescoping members, against 125 which the work is fed when the device is applied to the platen and operating to prevent rotation of the one of said telescoping members carrying it.

130 5. A gage device for the purpose set forth,

comprising a bearing-member, an internally and externally threaded member with its threads oppositely inclined, said last-named member having threaded connection at one 5 of its threads with said bearing-member, and a threaded rod telescoping with said second-named member and engaging the internal threads thereof, said rod having a stop surface against which the work is fed 10 when the device is applied to a platen.

6. A gage device for the purpose set forth, comprising a bearing-member, an internally and externally threaded member with its threads oppositely inclined, said last-named 15 member having threaded connection at one of its threads with said bearing-member, a threaded rod telescoping with said second-named member and engaging the internal threads thereof, and a foot secured to the 20 outer end of said rod, said foot serving as a stop for work and preventing rotation of said rod when the device is applied to position on a platen.

7. A gage device for the purpose set forth, 25 comprising a bearing-member, a member having threaded connection with said bearing-member, a third, oppositely threaded, member having threaded connection with said second-named member, a foot affording 30 a stop surface, and releasable means engaging said foot and third member and operating to releasably hold said third member against rotation.

8. A gage device for the purpose set forth, 35 comprising a bearing-member, a member having threaded connection with said bearing-member, a third, oppositely threaded, member having threaded connection with said second-named member, the outer end

of said third-named member being non-circular, and a foot affording a stop surface and provided with a section adapted to fit over the outer end of said third member and be longitudinally shifted thereon, said foot-member being adapted to engage the non-circular portion of said third member and hold the latter against rotation and be shifted lengthwise from such position to permit said third member to rotate independently 45 of said foot-member.

9. A gage device for the purpose set forth, comprising a bearing-member equipped with a relatively thin extension adapted to be inserted between a platen and its coöperating bail, a tube-member threaded on its exterior and interior surfaces with the threads oppositely inclined, said tube-member having threaded connection with said bearing-member, a rod threaded externally and engaging the internal threads of said tube-member, and a foot carried on the outer end of said rod and operating when the device is applied to position on a platen to prevent 50 rotation of said rod.

10. A gage device comprising a bearing 65 member adapted to be secured in position relative to a platen, and telescoping members adjustable longitudinally of each other, one of said telescoping members being longitudinally adjustable on said bearing member and the inner one of said telescoping members being provided with a stop-surface 70 for work fed to the press.

JOSEPH F. GEARY.
